GAUGING MEANS FOR SHOE MACHINES

Arthur L. Russell, Boston, and John T. Lancaster, Newton, Mass., assignors to United Shoe Machinery Corporation, Flemington, N. J., a corporation of New Jersey

Application January 25, 1941, Serial No. 375,960

29 Claims. (Cl. 1—32)

This invention relates to machines for operating upon portions of shoes, it being especially applicable to the attachment of heel-parts, as bases and top-lifts.

In heel-attaching machines, a shoe, presented to fastening-inserting mechanism upon a jack or like support, is capable of some angular movement about the longitudinal axis of the jack. An example of a machine in which this may occur is found in Letters Patent of the United States No. 1,157,688, Glidden, October 26, 1915. To locate the heel-seat of the shoe in the proper relation to a heel or a top-lift presented in a swing-plate or other holder, the operator varies the angle of the shoe about the axis of the jack, until he believes that the breast-line of the heel or top-lift lies at a correct angle across the shank-portion of the shoe, and the peripheries of the heel-seat and those of the heel-parts agree in contour. This is commonly effected by mere inspection of the work, a method which does not give satisfactory results unless the operator is highly skillful, or an undue amount of time is spent. An object of this invention is to enable an operator to determine rapidly and accurately the angular position of a shoe with relation to a part to be attached to it, this being accomplished by compactly arranged means which in no way interferes with the manipulation of the work or of parts of the machine. In the attainment of this object, there is combined with such operating mechanism as that for inserting fastenings and with a co-operating jack, or other shoe-support, gaging means to which the forepart of a supported shoe may be directly referred, said gaging means being so mounted as to be unaffected by movement of the support. When the support is located above the inserting mechanism, as is often the case, the gaging means is normally arranged entirely below the work, so the operator is not inconvenienced by its presence. To provide for use with shoes of different dimensions, the gaging means is movable upon its mounting. Machines of the type of that disclosed in the previously mentioned patent, often have a guard to protect persons against injury by the inserting mechanism, and when such a device is present, it furnishes an effective mounting for the gaging means. The gaging means, which we prefer to employ, is supplied by an image or images produced upon a portion of the machine as a contrasting effect of light and shade by a source of light, which, when there is a guard, may be situated therein. By reference to these images the operator may position the

work. The invention, as herein disclosed, utilizes spaced electric lights between which and the shoe-support translucent screens are interposed, while gauging means, which may consist of slotted plates, are interposed between the lights and the screens. These plates or gauging devices are variable in their location to adapt them to the positioning of right and left shoes of different widths and forms, and also to establish them in the correct relation to the shoe-support. This may be effected by connecting them to a right-and-left screw, and by making said screw adjustable longitudinally of its axis. To prevent leakage of light past the gauge-plates, shutters may be movable with each plate at opposite sides of its slot.

One of the several forms which the invention may assume is illustrated in the accompanying drawings, in which

20 Fig. 1 shows our improved shoe-gauging means in broken side elevation and associated with a heel-attaching machine;

Fig. 2 is a broken top plan view of one of the gauging devices;

25 Fig. 3, a vertical transverse section through the guard of the heel-attaching machine;

Fig. 4, a broken detail in side elevation of a connecting device included in the conductors which supply current to the gauge-lights; and

30 Fig. 5, a section on the line V—V of Fig. 4.

At 10 appears the frame of a heel-attaching machine of the character already referred to. In this frame is arranged for vertical reciprocation a crosshead 12, carrying the die-block of nail-35 or other fastening-inserting mechanism, and a crosshead 14 upon which are mounted drivers operating in the passages of the die-block. At 16 upon the crosshead 12 is shown a fragment of the usual swing-plate, for holding a heel and top-lift and presenting them successively to the attaching mechanism. Above the crosshead 12 is a shoe-supporting jack 18, with which is associated a back-stop 19. At the front of the inserting mechanism a protective device or guard 20 is hinged at 22. It is closed at the front and open at the rear, being thus recessed. When the guard is swung down from the position illustrated in the drawings, access may be had to the inserting mechanism.

50 Within the guard, projecting upwardly from the bottom near opposite sides, are perforated bosses 24, 24, each furnishing a seat for an incandescent-light-socket 26. In each socket is a light-bulb 28, the effective illumination of which may be increased by painting the interior of the

guard white. Above each bulb, inserted in the horizontal top of the guard, is a translucent plate or screen 30, which may be of a plastic sufficiently resistive to breakage. Across the upper rear portion of the guard a spindle 32 is rotatable, there being formed upon it right-and-left screws 34, 34. For convenience in assembling, this spindle is in two sections joined by a coupling 36. In threaded engagement with each screw of the spindle is a lug 38 upon a horizontal plate 40, this plate having its forward extremity guided to slide at 42 upon the guard and lying beneath the corresponding screen 30. Partially across each plate 40, from front to rear of the guard, a gauge-slot 44 extends, and beneath this may be set a strip 46 of a transparent or translucent colored plastic. In all positions of the plate 40 effected by rotating the spindle 32, the slot 44 will lie beneath the screen 30, producing thereon an image in the form of a colored line. By reference to the two spaced lines upon the screens, the maximum projection of right-and-left shoe-soles near the ball-lines may be positioned to give the angular relation of the shoes upon the support to the heel or top-lift in the swing-plate 16 to correctly locate the heel-seat for the attachment of the heel-parts. Obviously, the images, instead of being furnished by lines of light, might consist of shadows cast by a solid light-arresting strip interposed between the bulbs 28 and the screens 30. What is important is that there shall be a contrasting effect of light and shade, furnishing a gauge to which the work may be referred. As the width or degree of projection of the shoe-sole changes, the gauging images may correspondingly be adjusted simultaneously toward or from each other along the screws 34, 34, by rotating the spindle 32 through a finger-piece 50 thereon. As an initial or setting-up adjustment, the spindle may be moved bodily longitudinally of its axis. To accomplish this, a sleeve 52 surrounds the spindle at the end opposite the finger-piece 50, it being threaded into the side wall of the guard 20. Upon this sleeve is a finger-piece 54, and at its opposite extremities are collars 56, 56, fast upon the spindle. By turning the finger-piece 54, the spindle with the two gauge-plates 40, 40 may be adjusted together in the same direction for the purpose just indicated.

For the extreme widths of shoe-soles which are to be positioned, the extent of travel of the plates 40 must be considerable, and the light which is projected from the bulbs 28 toward the screens 30, should be confined to that passing through the slots 44. Were the plates alone to cover the screens, it would require said plates to be so wide that the transverse dimension of the guard 20, necessary to contain them, might become excessive. To avoid this, there is arranged to slide in recesses at the opposite sides of the slot 44, in each of the plates, a shutter 60. As is best shown in Fig. 2 of the drawings, in each shutter there are three grooves, two of these, 62, 62, being in the upper face, and the third, 64, in the lower face. Into the grooves 62 project the points of screws 66, 66 threaded downwardly through the top of the guard. A screw 68 similarly enters each groove 64, it being threaded upwardly through the plate 40. The ends of the grooves and the screws are so related, that, when the plates are shifted to the left, after a certain amount of travel, the screws 66 engaging the right ends of their grooves hold back the right shutters, to maintain closed the space be-

tween the right ends of the plates and the top wall of the guard. Thereafter, upon movement of the plates to the right, the screw 68 contacts with the right end of its groove and carries the shutter with it. An opposite effect is produced for the left shutters. For movement of the plates 40 to the right, the action of the shutters is reversed over that for the preceding adjustment.

10 To supply current for the bulbs 28, an armored cable 70 may lead into the heelng machine, it being cleated in place upon the frame at 72 near the guard-hinge 22. The conductors of the cable may be continued by a flexible pair 74, joined in parallel to the terminals of the sockets 26. As the guard 20 is frequently swung down upon its hinge, to avoid fretting of the conductors there is interposed between the cable and the flexible pair a connecting device C. As appears in Figs. 4 and 5, this device is made up of two portions enclosed in casing-sections 76 and 78, formed of insulating material. Both sections surround the hinge-pin 22, 76 being loose upon it but held against turning by the cable 70. The section 78 is fast upon the hinge-pin. The conductors of the cable are attached to arcuate terminal blocks 80, 80 secured to the casing-section 76. Upon these blocks bear contact-springs 82, 82, fixed to the casing-section 78 and to which the conductors of the pair 74 are joined. The casing-sections are yieldably forced together by an expansion-spring 84, interposed between the section 76 and a collar 86 secured to the hinge-pin. As the guard is turned upon its hinge, the springs slide over the terminal-blocks, maintaining the circuit without stresses being set up in the conductors.

15 In heelng a pair of shoes, the operator, by rotating the hand-wheel 50, and, therefore, the right-and-left threaded spindle 32, will move the gauge-plates 40, 40 either toward or from each other. This will, for the work in hand, locate upon the screens 30, 30 images in the form of narrow illuminated strips extending across the top of the guard 20, from front to rear of the heelng machine, and produced by the light passing upwardly from the two electric lamps 28, 28 through the gauge-slots 44, 44. Jacking one shoe of a pair, as the right, and supplying a heel and a top-lift to the swing-plate 16, the operator will glance down at the left image seen upon its screen, and so turn the shoe about the vertical axis of the jack that the maximum projection of the sole, near the ball-line, will be vertically aligned with such image. This correctly positions the heel-seat of the shoe with respect to the heel. The length of the gauging image is sufficient to make it effective for all sizes of shoes. For different widths, only infrequent adjustment of the gauge-plates is necessary, because the arcs subtended by the angles through which the shoes must be swung is small at the heel-seat as compared with that at the forepart. Therefore, one setting of the gauging means is sufficiently accurate for a considerable range of widths. After the machine has been actuated, and the heel nailed, the work may be similarly gauged for the attachment of the top-lift. The procedure for the left shoe is the same, save that it is positioned by reference to the right-hand image. The light from the lamps 28 is visible only through the slots 44, all the light-rays at the edges of the plates 40 which might distract the operator being cut off by the shutters 60. The entire gauging organization is removed from the field of operation, adds almost

nothing to the bulk of the machine, and in no way interferes with access to or movement of any part.

Having described our invention, what we claim as new and desire to secure by Letters Patent of the United States is:

1. In a machine for attaching heel-parts to shoes, fastening-inserting mechanism, a movable shoe-support co-operating therewith, gauging means to which the forepart of a supported shoe may be directly referred and a mounting for the gauging means unaffected by movement of the shoe-support.

2. In a machine for attaching heel-parts to shoes, fastening-inserting mechanism, a shoe-support situated above the inserting mechanism to co-operate therewith, and gauging means for a supported shoe, said gauging means being adjacent to the inserting mechanism and normally entirely below the work.

3. In a machine for attaching heel-parts to shoes, a frame, fastening-inserting mechanism and a shoe-support movable upon the frame, gauging means for a supported shoe mounted upon the frame independently of the inserting mechanism and support, and means arranged to move the gauging means upon its mounting to vary the position at which the forepart of the shoe may be presented to it.

4. In a machine for attaching heel-parts to shoes, fastening-inserting mechanism, a shoe-support co-operating therewith, a guard for the inserting mechanism, and gauging means for a supported shoe mounted upon the guard.

5. In a machine for attaching heel-parts to shoes, fastening-inserting mechanism, a shoe-support co-operating therewith, a guard for the inserting mechanism, and gauging means for a supported shoe arranged to move upon the guard.

6. In a machine for attaching heel-parts to shoes, fastening-inserting mechanism, a shoe-support co-operating therewith, a guard movable to either cover or give access to the inserting mechanism, and gauging means for a supported shoe movable with the guard.

7. In a machine for operating upon shoe-parts, a shoe-support, mechanism for operating upon a supported shoe, and lighting means producing an image, said image furnishing a gauge by reference to which a supported shoe may be positioned.

8. In a shoemaking machine, the combination with means for performing an operation on a shoe, of means for producing a contrasting effect of light and shade cast upon a portion of the machine and furnishing a reference device with relation to which an operator may correctly position the work.

9. In a machine for operating upon shoe-parts, a shoe-support, mechanism for operating upon a supported shoe, lighting means producing an image upon a portion of the machine, said image furnishing a gauge by reference to which a supported shoe may be positioned, and means arranged to vary the location of the image upon the machine.

10. In a machine for operating upon shoe-parts, a shoe-support, mechanism for operating upon a supported shoe, and lighting means producing a plurality of images, said images furnishing spaced gauges by reference to which supported right and left shoes may be positioned.

11. In a machine for attaching heel-parts to shoes, fastening-inserting mechanism, a shoe-support co-operating therewith, a guard for the 75

inserting mechanism, and lighting means mounted upon the guard and producing an image, said image furnishing a gauge by reference to which a supported shoe may be positioned.

5 12. In a machine for operating upon shoe-parts, a shoe-support, mechanism for operating upon a supported shoe, an electric light associated with the operating mechanism, a screen interposed between the light and the support, and gauging means interposed between the light and the screen.

13. In a machine for operating upon shoe-parts, a shoe-support, mechanism for operating upon a supported shoe, an electric light associated with the operating mechanism, a screen interposed between the light and the support, and light-arresting means movable between the light and the screen.

14. In a machine for operating upon shoe-parts, a shoe-support, mechanism for operating upon a supported shoe, an electric lamp associated with the operating mechanism, a translucent plate interposed between the lamp and the support, and a gauge device past which light from the lamp travels to the translucent plate.

15. In a machine for operating upon shoe-parts, a shoe-support, mechanism for operating upon a supported shoe, an electric lamp associated with the operating mechanism, a translucent plate interposed between the lamp and the support, a gauge device past which the light from the lamp travels to the translucent plate, and means arranged to vary the position of the gauge device.

16. In a heel-attaching machine, nailing mechanism, a jack situated above the nailing mechanism to co-operate therewith, an electric light situated in front of the nailing mechanism, a translucent screen interposed between the light and the jack, and a slotted plate interposed between the light and the screen.

17. In a heel-attaching machine, nailing mechanism, a jack situated above the nailing mechanism to co-operate therewith, an electric light situated in front of the nailing mechanism, a translucent screen interposed between the light and the jack, a slotted plate interposed between the light and the screen, and means arranged to vary the position of the plate transversely of the jack.

18. In a heel-attaching machine, nailing mechanism, a jack situated above the nailing mechanism to co-operate therewith, spaced electric lights situated at the front of the nailing mechanism, translucent screens interposed between the respective lights and the jack, and a slotted gauge-plate interposed between each light and its screen.

19. In a heel-attaching machine, nailing mechanism, a jack situated above the nailing mechanism to co-operate therewith, a light situated at the front of the nailing mechanism, a translucent screen interposed between the light and the jack, a slotted gauge-plate interposed between the light and the screen, and a shutter movable with the gauge-plate at each side of the slot.

20. In a heel-attaching machine, nailing mechanism, a jack situated above the nailing mechanism to co-operate therewith, spaced electric lights situated at the front of the nailing mechanism, translucent screens interposed between the respective lights and the jack, a slotted gauge-plate interposed between each light and its screen, a shutter movable with each gauge-plate at each side of the slot, and means for limiting the movement of each shutter.

21. In a heel-attaching machine, nailing mechanism, a jack situated above the nailing mechanism to co-operate therewith, spaced electric lights situated at the front of the nailing mechanism, translucent screens interposed between the respective lights and the jack, a slotted gauge-plate interposed between each light and its screen, and means arranged to move the gauge-plates toward and from each other. 5
22. In a heel-attaching machine, nailing mechanism, a jack situated above the nailing mechanism to co-operate therewith, spaced electric lights situated at the front of the nailing mechanism, translucent screens interposed between the respective lights and the jack, a slotted gauge-plate interposed between each light and its screen, means arranged to move the gauge-plates toward and from each other, and means arranged to move the gauge-plates together transversely of the jack. 10
23. In a heel-attaching machine, nailing mechanism, a jack situated above the nailing mechanism to co-operate therewith, a guard for the nailing mechanism, said guard having at its top translucent portions, two electric lights mounted within the guard beneath the translucent portions, and light-arresting means interposed between each light and the translucent portion of the guard. 15
24. In a heel-attaching machine, nailing mechanism, a jack situated above the nailing mechanism to co-operate therewith, a guard for the nailing mechanism, said guard having at its top a translucent portion, an electric light mounted within the guard beneath the translucent portion, a slotted plate interposed between the light and the translucent portion of the guard, and a shutter movable at each side of the slotted plate between it and the guard. 20
25. In a heel-attaching machine, nailing mechanism, a jack situated above the nailing mechanism to co-operate therewith, a guard for the nailing mechanism, said guard having at its top translucent portions, two electric lights mounted within the guard beneath the translucent portions, a slotted plate interposed between each light and a translucent portion of the guard, and a shutter movable at each side of each slotted plate between it and the guard, there being grooves in each shutter extending in the direction of its movement and projections extending from the plate and guard into the grooves. 25
26. In a heel-attaching machine, nailing mechanism, a jack situated above the nailing mechanism to co-operate therewith, a pivoted guard for the nailing mechanism, said guard having at its top a translucent portion, an electric lamp mounted within the guard beneath the translucent portion, supply conductors for the lamp, light-arresting means interposed between the lamp and the translucent portion of the guard, and a contact device associated with the pivot of the guard and having relatively movable portions by which the circuit through the conductors is maintained. 30
27. In a heel-attaching machine, nailing mechanism, a jack situated above the nailing mechanism to co-operate therewith, a guard for the nailing mechanism, said guard having at its top translucent portions, two electric lights mounted within the guard beneath the translucent portions, a right-and-left screw rotatable at the top of the guard, and a slotted plate interposed between each light and a translucent portion of the guard and having threaded engagement with one of the portions of the screw. 35
28. In a heel-attaching machine, nailing mechanism, a jack situated above the nailing mechanism to co-operate therewith, a guard for the nailing mechanism, said guard having at its top translucent portions, two electric lights mounted within the guard beneath the translucent portions, a right-and-left screw rotatable at the top of the guard, a slotted plate interposed between each light and a translucent portion of the guard and having threaded engagement with one of the portions of the screw, and means arranged to move the screw upon the guard longitudinally of its axis. 40
29. In a heel-attaching machine, nailing mechanism, a jack situated above the nailing mechanism to co-operate therewith, a guard for the nailing mechanism, said guard having at its top translucent portions, two electric lights mounted within the guard beneath the translucent portions, a right-and-left screw rotatable at the top of the guard, a slotted plate interposed between each light and a translucent portion of the guard and having threaded engagement with one of the portions of the screw, and a sleeve threaded into the guard and in which the screw is rotatable. 45
